United States Patent Office

Des. 223,151
Patented Mar. 21, 1972

223,151

CAMPER

Grant W. Stroud, 920 21st St., Lewiston, Idaho 83501

Filed Oct. 16, 1970, Ser. No. 25,530

Term of patent 14 years

Int. Cl. D12—10

U.S. Cl. D14—3

FIG. 1

FIG. 2

FIG. 3

FIG. 4

FIG. 5

FIG. 6

FIG. 7

FIG. 8

FIG. 1 is a front perspective view of the camper;
 FIG. 2 is a top view of the camper as shown in FIG. 1;
 FIG. 3 is a front view of the camper as shown in FIG. 1;

FIG. 4 is a side view of the camper as shown in FIG. 1, the opposite side being a mirror image thereof;

FIG. 5 is a rear view of the camper as shown in FIG. 1;

FIG. 6 is a front perspective of the camper with the canopy retracted;

FIG. 7 is a side view of the camper as shown in FIG. 6;

FIG. 8 is a top view of the camper as shown in FIG. 6.
 I claim:

The ornamental design for a camper, as shown and described.
